Primary Examiner — Patricia A Palasik(74) *Attorney, Agent, or Firm* — Grossman, Tucker, Perreault & Pfleger, PLLC(57) **CLAIM**

The ornamental design for a gripper for robot, as shown and described.

DESCRIPTION

FIG. 1 is a front view of a gripper for robot of the present invention;

FIG. 2 is a rear view of the gripper for robot shown in FIG. 1;

FIG. 3 is a left side view of the gripper for robot shown in FIG. 1;

FIG. 4 is a right side view of the gripper for robot shown in FIG. 1;

FIG. 5 is a top view of the gripper for robot shown in FIG. 1; and,

FIG. 6 is a front perspective view of the gripper for robot shown in FIG. 1.

The broken lines in the drawings depict portions of the gripper for a robot that form no part of the claimed design.

1 Claim, 6 Drawing Sheets(56)
